(57) CLAIM

The ornamental design for a travel bag as shown and described.

DESCRIPTION

FIG. 1 is a top perspective view of a travel bag;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is an inside view thereof.

FIG. 9 is an inside view thereof.

FIG. 10 is an inside view thereof; and,

FIG. 11 is an inside view thereof.

In the drawings, the broken lines depict portions of the travel bag that form no part of the claimed design.

1 Claim, 11 Drawing Sheets
